INVENTOR
Magnien Clemence
ATTORNEY

UNITED STATES PATENT OFFICE.

MAGNIEN CLÉMENCE, OF COFFEYVILLE, KANSAS.

METHOD OF AND APPARATUS FOR WAVING HAIR.

Application filed October 30, 1926. Serial No. 145,190.

My invention relates to a method of and apparatus for waving hair.

Under ordinary methods of imparting what is commonly termed a "permanent wave" to hair, it is customary to coil the locks of hair individually on cores, applying flannels to the hair and then heating the hair in a tube to impart semi-permanency to the coil.

10 While I follow the former method in its more general aspects, it is the object of my invention to impart to the locks of hair a reverse curve as distinguished from the coil, and in accomplishing this object I employ a pair of cores upon which the hair is wound back and forth and to which the hair is held securely during the waving and heating operations, so that when the cores are removed the locks of hair will remain 20 in the reversely curved or waved formation.

In the accompanying drawings illustrating various steps of the method,

Fig. 1 is a perspective view of a pair of cores and a lock of hair, showing the flexible 25 tie member whereby the hair is attached to the core.

Fig. 2 is a similar view showing a lock of hair partially applied to the cores.

Fig. 3 is a perspective view of the cores, 30 showing the lock of hair wound thereon and tied thereto.

Fig. 4 is a similar view of the opposite side of the cores.

Fig. 5 is a perspective view of a lock 35 of hair after the waving operation has been completed.

Fig. 6 is a view of the hair after a comb has been passed through it.

Referring more in detail to the drawings:—

1 and 2 designate a pair of cores which individually correspond to the cores commonly employed for waving hair, each having a lip 3 at one end provided with a slit 4 and having lateral ears 5 pivotally connected by a pin 6 to hingedly connect the cores at one end. 7 designates a lock of hair and 8 a cord or string attached to the lock of hair at the point where the wave is 45 to start, the string or cord being preferably loop tied at its center to the hair and extended in separate strands 9 and 10.

When the string or cord is tied to the hair as described, one of the strands is ex-

tended through the slit in the lip on one 55 of the cores, and the lock of hair with the strand last mentioned is wound back and forth in reverse curves over the pair of cores. When the lock of hair is wound on the cores as described, the second strand of 60 the string or cord is wrapped about the hair and its end tied to the end of the first strand which has followed the lock of hair in its windings about the core, to securely attach 65 the hair to the cores.

With the hair tied to the cores as described, the ordinary flannel is applied to the hair and the cores with the hair thereon extended into the ordinary heating tube indicated at 11, and heat applied as in the 70 ordinary process of waving.

After the hair has been heated to the proper temperature and for a sufficient length of time, the heat is turned off, the cores removed from the tube, the strings 75 untied and the cores removed from the hair, leaving the hair in waves as illustrated in Fig. 5. When the hair is combed the wave is retained but spread, as shown in Fig. 6.

It is apparent that by my method and with the apparatus described and illustrated in the accompanying drawings, I am able to provide an actual wave in the hair as distinguished from merely coiling, and that the wave is set to constitute a relatively 85 permanent formation.

What I claim and desire to secure by Letters Patent is:—

1. The method of waving hair comprising coiling the hair in reverse curves on 90 separate cores, tying the hair to the cores, wrapping the hair on the cores, heating the hair, and removing the wrapping and cores from the hair.

2. The method of waving hair comprising attaching a double string to the hair, coiling the hair and one of the strings in reverse curves on a pair of cores, wrapping the other string about the hair and cores, tying the ends of the strings, wrapping the hair, heating the hair, and removing the 100 wrapping, cores and the string from the hair.

3. Apparatus for waving hair comprising a pair of cores, hinged at one end, a heating tube adapted to receive the cores and the hair wrapped thereon, and a double strand string attached to the hair, with one 105

of the strands wound on the cores with the hair and the other wound about the hair on the cores.

4. Apparatus for waving hair comprising a pair of cores having hinge connection at one end, a heating tube adapted to receive the cores and the hair wrapped thereon, a double strand string attached to the hair,

with one of the strands attached to one of the cores and wound on the cores with the hair, the other strand of the string wound about the hair on the cores, and the two ends of the string being tied to hold the cores together and the hair on the cores.

In testimony whereof I affix my signature.

MAGNIEN CLÉMENCE.
